SHOCK ABSORBING MECHANISM

Lawrence A. Wilson, Apalachin, Benjamin M. Durfee, Binghamton, and Harry J. Tashjian, Endwell, N.Y., assignors to International Business Machines Corporation, New York, N.Y., a corporation of New York

Application November 15, 1956, Serial No. 622,421

2 Claims. (Cl. 74—216.5)

The present invention relates generally to shock absorbing mechanisms and more particularly to a mechanism for absorbing the shock developed in a belt drive.

In machines such as, for example, IBM card feeding machines, high starting and stopping torques cause breakage in the timing belts which connect the various operating parts. Therefore, for convenience, the present invention will be described in connection with an IBM card feeding machine, it being understood that the invention is not limited thereto.

The present invention provides generally a shock absorbing drive mechanism which will prevent breakage in the timing belt drives. The driven elements of the machine are divided into two groups: those in which no movement such as oscillation can be tolerated, and those in which some small oscillatory movement may be tolerated.

Accordingly, the driven elements of the machine in which no movement may be tolerated must be connected directly to the driver clutch shaft by a positive drive means, and the elements of the machine in which some small oscillatory movement may be tolerated are connected to the driver clutch shaft through the shock absorbing mechanism of the present invention.

Generally, the present invention comprises two spaced-apart idler pulleys between which a timing belt is passed to operably connect a power clutch shaft to one or more load shafts. The idler pulleys are yieldably maintained in a predetermined position by one or more suitable resilient means such as, for example, coil springs which allow the pulleys to shift to absorb starting and stopping shock tensions developed in the belt.

Therefore, one of the objects of the present invention is to provide a mechanism for absorbing shock tensions developed in belt drives.

Another object of the present invention is to provide a means for controlling the tension in a belt drive.

The invention further resides in certain novel features of parts and further objects and advantages therein will become apparent to those skilled in the art to which it pertains from the following description of the present preferred embodiment thereof described with respect to the accompanying drawing in which the single figure illustrates the preferred embodiment of the present invention.

Referring now to the single figure in the drawing, the operating elements of a card feeding machine are illustrated as being divided into two groups: those elements 11 in which some movement or oscillation may be tolerated, and those elements 12 in which no movement or oscillation may be tolerated. The card feeding mechanism 12 is selected to illustrate that portion of a card feeding machine which must stop instantly with the power clutch shaft and, therefore, is shown as being driven directly by means of a flexible belt 13 from a power clutch shaft 14. Therefore, from the direct connection of the card feeding mechanism 12 to the power clutch shaft 14 it may be seen that the card feeding mechanism 12 will stop at the instant that the power clutch shaft 14 stops.

2

The feed rollers 21, 22 and 23 are illustrated as the elements 11 of the card feeding machine in which some movement or oscillation may be tolerated. A flexible belt 24 with teeth 25 connects the two feed rollers 21 and 22 with the power clutch shaft 14. The connection of two feed rollers 21 and 22 is shown for illustration purposes only. Obviously the flexible belt 24 may connect only one feed roller with the power clutch shaft 14, or it may connect a plurality of feed rollers to the power clutch shaft. Therefore, for descriptive purposes only, this invention will be described in connection with the two feed rollers 21 and 22.

A flexible belt 24 with teeth 25 drives the two feed rollers 21 and 22 from a power clutch shaft 14. The flexible belt 24 is shown in operable relationship with gears 27 and 28 which are secured to the shafts 18 and 19, respectively, as are the feed rollers 21 and 22, respectively. The flexible belt 24 passes between two idler pulleys 31 and 32 which keep the belt 24 taut during operation. A gear 33 which is mounted on the power clutch shaft 14 drives the flexible belt 24 to rotate the feed rollers 21 and 22.

The two idler pulleys 31 and 32 are mounted on an elongated arm 34 which is wedge-shaped, as shown in the drawing. The point 36 of the wedge is pivoted about an axis 37 on the base (not shown) of the machine. At the opposite end of the elongated arm 34 an integral extended portion 38 is formed.

An aperture 39 located in the extended portion 38 allows a rod 41 to be extended therethrough. The rod 41 may be threaded into a base portion 42 of the machine, or it may be mounted on the base 42 by any suitable means, as for example, by a nut 43 threaded on the end 44 of the rod 41.

A first spring 46 mounted about the rod 41 bears against the base portion 42 at one end 47 and at the opposite end 48 against one side of the extended portion 38. A second spring 50, which is similar to spring 46, bears at the end 53 against a nut 49 threaded onto the end 51 of rod 41 and at the end 52 against the opposite side of the extended portion 38 from the spring 46. Obviously, however, the two springs 46 and 50 may be replaced by a single spring which may bear against the base portion 42 at one end 47 and against the nut 49 at the end 53 with the extended portion 38 being secured to the spring at a point approximately midway between ends 47 and 48.

Another gear 55 may be mounted so that the movement of the two feed rollers 21 and 22 will cause movement in a further feed roller 23 in the machine. Additional rollers 56, 57 and 58 may be mounted to bear against the feed rollers 21, 22 and 23, respectively, in order to keep cards fed into the machine in close contact with the feed rollers.

In operation, the power clutch shaft 14 with the power gear 33 mounted thereon starts by turning, for example, in a clockwise direction. The feed rollers 21 and 22 resist this turning due to their inertia and, therefore, excessive tension would be developed in the flexible belt 24. However, the elongated arm 34 will pivot about a pivot point 37 in a clockwise direction due to the pull by the flexible belt 24 against the idler pulley 31 and the extended portion 38 will compress spring 50 to absorb the initial tension developed in the flexible belt 24. After the machine has started, the elongated member 34 will move back toward its initial position which position is illustrated in the drawing and will oscillate thereabout (approximately two oscillations of significant magnitude) until it finally comes to rest. The flexible belt 24 is kept taut during this cycle due to the relationship of the two idler pulleys 31 and 32.

In stopping the machine, the power clutch shaft 14

stops in an instant. However, the feed rollers 21 and 22 will have a tendency to continue to rotate due to their inertia. The elongated arm 34 will then be pulled in a counterclockwise direction against spring 46 to absorb the tension developed in the flexible belt 24. After the feed rollers 21 and 22 come to rest, they will rotate in the opposite direction and oscillate as the elongated arm 34 seeks its rest position. Thus, the shock, which ordinarily would be absorbed in the flexible belt 24, will now be absorbed in the springs 46 and 50 and belt breakage from this cause will be avoided.

It may be readily seen that the present invention provides a shock absorbing drive mechanism which will absorb both starting and stopping shock on that part of the load which can tolerate oscillation, and at the same time provide a home position, due to the spring arrangement, which allows a positive timing relationship between the drive and the card displacement.

It will be understood that the embodiment herein described is merely illustrative of the invention and one application thereof, and that modifications can be made and it is capable of other applications.

We claim:

1. A shock absorbing drive mechanism for driving at least one load shaft comprising a power shaft, an elongated idler arm rotatably mounted at one end, two spaced-apart idler pulleys mounted adjacent each other on said idler arm at a distance from said rotatably mounted end, flexible belt means mounted about said power shaft and said load shaft and passing between and engaging said two idler pulleys, an extended portion on said idler arm

5 attached to the end near said idler pulleys, and a spring means connected to said extended portion to resiliently resist movement of the idler arm from a predetermined position.

2. A shock absorbing drive mechanism for driving a plurality of load shafts comprising a power shaft, a wedge-shaped idler arm rotatably mounted at one end, two spaced-apart idler pulleys mounted adjacent each other on said idler arm at a distance from said rotatably mounted end, flexible belt means mounted about said power shaft and said plurality of load shafts and passing between and engaging said two idler pulleys, an extended portion on said idler arm attached to the end near said idler pulleys and having an aperture therethrough, rod means extending through said aperture in said extended portion, and spring means about said rod means bearing against each side of said extended portion to resiliently resist movement thereof.
